UNITED STATES PATENT OFFICE.

ROBERT E. CAMPBELL, OF BERKELEY, CALIFORNIA.

GAS-HEATER.

1,232,457.

Specification of Letters Patent.

Patented July 3, 1917.

Application filed January 26, 1916. Serial No. 74,354.

To all whom it may concern:

Be it known that I, ROBERT E. CAMPBELL, a citizen of the United States, residing at Berkeley, in the county of Alameda and State of California, have invented new and useful Improvements in Gas-Heaters, of which the following is a specification.

This invention relates to a gas heater. The object of the present invention is to provide an improved casing construction in combination with a burner of the Bunsen type in which casing is produced a more complete combustion of the gas for rendering the heater more efficient as a heat generator without the odors usually produced.

The invention consists of the parts and the construction and combination of parts as hereinafter more fully described and claimed, having reference to the accompanying drawings in which—

Figure 1 is a central vertical section through the heater.

Fig. 2 is a plan view of same.

Referring to the drawings in detail, A indicates a horizontally positioned pipe secured in a rectangular shaped open bracket 2. One end of the pipe is connected by a hose 3 with a suitable source of gas supply, while the other end is closed by the bracket 2. Mounted in the bracket 2 in alignment with a discharge orifice 4 formed in pipe A in a vertical position and in direct alignment with the orifice is a mixing tube 5. The lower end of this tube is preferably screwed into the bracket 2 and it is therefore possible to raise and lower the tube or to adjust the tube vertically with relation to the discharge orifice. Discharge of gas from the orifice shown produces a nozzle action which draws air in through the tube in direction of arrows α . A comparatively perfect mixture of air and gas is thus obtained, which, when ignited, produces a flame approximately of the shape shown at 6. A burner 45 constructed as here shown, operates on the Bunsen principle. The flame 6 produced by the mixture of air and gas passing through the tube 5 is blue in color and produces an intense heat. The combustion of the gas and air mixture discharging, is however, not perfect, as a considerable quantity of unconsumed gas escapes from the flame, causing an unnecessary odor and waste, which, in this instance, is obviated by the provision 55 of a secondary combustion tube indicated at B. The lower end of this tube is preferably

enlarged and cone-shaped as at 7 and is positioned vertically in direct alignment with the mixing tube 5. It is preferably mounted in the position shown or just sufficiently far above the tube 5 to permit the flame 6 to enter the lower end of same. The flame 6 projected into the secondary tube B immediately causes air to enter in the direction of arrows b . The air thus entering and mixing with the flame 6 is just sufficient to produce a perfect combustion of the flame 6, and causes this to become extended to assume the dotted line position indicated at 8. The provision of the secondary tube B provides a means whereby a sufficient amount of additional air is brought into immediate contact with the primary flame 6 and the particles of gas escaping from same. A secondary combustion is in this manner produced which consumes everything escaping from the primary flame, thus generating more heat and at the same time eliminating the unnecessary odor and waste which would otherwise take place. While one type of Bunsen burner is here shown, it is obvious that any suitable type may be employed.

The secondary tube is surrounded by an exterior casing 9 which is supported by an ornamental iron stand 10. The lower end of the casing is preferably cone-shaped as at 11 and provided with a plurality of air intake openings 12 and at the upper end with a plurality of outlet openings 13. The casing forms a support for a deflecting plate 14 and a register 15 of any suitable construction. The Bunsen burner is carried by cross-arms 15', secured near the lower end of the ornamental stand and the upper end of the burner is preferably surrounded by a guard 95 which is constructed to produce an ornamental appearance conforming with the stand 10. In operation with the gas turned on and ignited, a flame of the shape indicated at 8 will be produced. A large volume 100 of air mixes with the flame as drawing action is first produced at the lower end of the mixing tube 5 which causes air to enter in the direction of arrows α . A second volume 105 of air is caused to pass through the secondary tube in the direction of arrows b through the action of the primary flame 6 entering the secondary tube B and a third volume of air is caused to pass through the openings 12 in the direction of arrows c , first by the action of the rising heat escaping from the upper end of the secondary tube B and

secondly by the radiating heat of the tube B. The large volume of hot air thus produced may either pass through the upper openings 13 or directly through the register 15, which may be opened or closed to direct the heat as desired. The deflecting plate 14 is provided for the purpose of deflecting the flame 8, thus preventing it from coming into direct contact with the register 15 and it furthermore causes the heat to be more evenly distributed through the top of the heater. The shape and size of the heater may be varied to suit different conditions and its materials and finish may be such as the experience of the manufacturer may dictate.

I wish it understood that the same is susceptible of modification and, therefore, changes in the construction and arrangement of the several parts may be employed without departing from the spirit of my invention as disclosed in the appended claims.

Having thus described my invention, what I claim and desire to secure by Letters Patent is—

1. In a gas heater, a burner, a combustion tube having a flared lower end terminating with an external annular shoulder and spaced above the burner, a casing in-

closing the upper end of the tube and having its lower portion contracted about the flared end of the tube and seating directly on the annular shoulder, said contracted portion being provided with a circular series of air inlet openings encircling the flared end of the tube, the upper portion of the casing having an outlet through which the gases from said tube pass intermingled with the air that enters through the series of inlet openings, and a support for the casing and tube.

2. In combination, a Bunsen burner having a burner tube, a long vertical tube arranged above the burner tube, a casing enclosing the upper end of the second tube and secured to the lower end of the latter, said casing having lower intake openings and upper outlet openings, a stand supporting the casing and Bunsen burner, and a guard for the burner supporting the lower end of the casing from the stand.

In testimony whereof I have hereunto set my hand in the presence of two subscribing witnesses.

ROBERT E. CAMPBELL.
